Filed Nov. 29, 1973, Ser. No. 420,006

Term of patent 14 years

Int. Cl. D16—13

U.S. CL. D6—209

FIG. 1 is a top plan view of a plastic floor matting embodying my new design, a complete design unit being shown, the broken line on the right of the figure indicating indeterminate length;

FIG. 2 is an enlarged cross sectional view taken on line 2—2 of FIG. 1; and

FIG. 3 is an enlarged cross sectional view taken on line 3—3.

The drawing has been lined for transparency.

I claim:

The ornamental design for a plastic floor matting, substantially as shown and described.
